UNITED STATES PATENT OFFICE.

ALBERT SCHMID, OF ALLEGHENY, AND J. CHARLES BECKFELD, OF RESERVE, ALLEGHENY COUNTY, PENNSYLVANIA.

GAS-ENGINE.

SPECIFICATION forming part of Letters Patent No. 371,793, dated October 18, 1887.

Application filed June 29, 1887. Serial No. 242,823. (No model.)

To all whom it may concern:

Be it known, that we, ALBERT SCHMID, a citizen of the Republic of Switzerland, residing at Allegheny, and J. CHARLES BECKFELD, 5 a citizen of the United States, residing at Reserve township, in the county of Allegheny and State of Pennsylvania, have invented or discovered certain new and useful Improvements in Gas-Engines, of which improvements 10 the following is a specification.

In Letters Patent No. 362,187, granted May 3, 1887, we have described and claimed a gas-engine having as its distinctive features the co-operation of the pistons and the valve for 15 regulating the flow of gas and air to the compression-cylinder and the exhaust of dead gases from the power-cylinder. In an engine constructed as set forth in said Letters Patent the explosive power of the gases is operative in one direction only—*i. e.*, to force the pistons outward—they being moved in the opposite direction or inwardly by the inertia of the fly or balance wheel.

The invention herein relates to a construction of engine wherein the explosive force of 25 the gas is utilized during the entire revolution of the engine, and wherein the same valves are operative in regulating the flow of gases to and from the several cylinders.

30 In the accompanying drawings, forming a part of this specification, Figure 1 is a sectional elevation of our improved engine, the section being taken on the line *y y*, Fig. 2. Fig. 2 is a similar view, the section being taken on the line *x x*, Fig. 1. Fig. 3 is a sectional elevation of the cylinders, the section being taken on the line *z z*, Fig. 2. Fig. 4 is a transverse section on the line *t t*.

In the practice of our invention the power-40 cylinders 1 and 1^a, compression-cylinders 2 and 2^a, and valve-chambers 3 and 4 are preferably formed in a single casting, which is supported on the crank-case 5, said case serving as a support or bed for the engine.

45 In the sides of the crank-case are formed the journals or bearings for the shaft 6, provided with crank-arms 7, arranged diametrically opposite to each other, as shown, and to the pins of said crank-arms are connected the lower ends of the pitmen or connecting-rods 8, whose upper end is connected in any suit-

able manner to the power or compression pistons in each cylinder. The power and compression cylinders are open at their lower ends, the power-cylinders opening into the 55 compression-cylinders, which are of a greater diameter than the power-cylinders. The pistons 9 and 9^a and 10 and 10^a are formed integral with each other.

Within the valve-chamber 3 is arranged 60 the valve 11, preferably of the piston-type, provided with the ports or passages 12 and 13 for the flow of gases to and from the cylinders when the valves are in proper relation to the several parts, as will be hereinafter stated. 65 Gas is admitted into the valve-chamber 3 through the ports 14 and 15, and air through the port 16 intermediate of the gas-ports, as shown in Figs. 1 and 2. The gas-ports 14 and 15 are so located with reference to the stroke 70 of the valve 11 that the port 14 will be uncovered by the upward movement of the valve and closed by its downward movement, while the port 15 is opened by the downward and closed by the upward movement of the valve, 75 the air-port 16 being constantly open. The explosive mixture formed by the commingling of the gas and air when either of the gas-ports is opened is conducted by the ports 17 or 18 into one or the other of the compression-cylinders, 80 the port 17 leading into the cylinder 2 and the port 18 into the cylinder 2^a at their upper ends. (See Fig. 1.) From the compression-cylinders the mixed gas and air are conducted by the ports 19 and 20 into the valve-chamber 85 4, in which is arranged the valve 21, provided with the port or passage 22, by which in certain positions of the valve the explosive mixture is conducted to the upper ends of one or the other of the power-cylinders through the 90 ports 23 or 24, the former leading to the cylinder 1 and latter to the cylinder 1^a. The power cylinders are made sufficiently longer than the stroke of the pistons 9 and 9^a to provide a chamber or space for the explosion 95 of the gas above the piston. A portion of the explosive mixture escapes by the ports 23 and 24 and port 25 to an igniter of any suitable construction located at the outer end of said port 25. The dead gases escape from the cylinder 1 by the port 26 into the valve-chamber 3, and thence by the passage 13, formed in the

valve 11, and the port 28 into the open air. The dead gases from the cylinder 1^a escape by the port 29 into the valve-chamber 3, and thence by the means above described into the 5 air.

The valves 11 and 21 are connected by rods 30 and 31 to eccentrics 32 and 33 on the power-shaft 6, the eccentric 32 being adjustable around or across the shaft through the medium 10 of the governor mechanism 34, all as fully described in the Letters Patent hereinbefore mentioned.

The several pistons and valves being in the position shown—*i. e.*, immediately after an explosion in the cylinder 1—and the valve 21 having moved down sufficiently far to cover the port 23, the operation of the engine is as follows: During the upward movement of the pistons 9 and 10 the pistons 9^a and 10^a are descending under the force of an explosion in the cylinder 1^a at or near the beginning of the descending stroke of the pistons 9^a and 10^a, the ports 15 and 18 are opened by the valve 11, which is also moving down, thereby admitting 25 a mixture of gas and air into the compressing-cylinder 2^a, the air-port 16 being constantly open, as before stated. An explosion having occurred in the cylinder 1, as above stated, the pistons 9 and 10 are forced downward and the pistons 9^a and 10^a upward. As the movements of the valve 11 are regulated to slightly precede the movements of the pistons in the cylinders—that is to say, the valve starts on its downward movement just prior 35 to the corresponding movement of the piston 9 and precedes the piston 9^a in its upward movement—it follows that just before pistons 9^a and 10^a move upward the valve 11 will close the ports 15 and 18. After the pistons 9^a and 40 10^a have accomplished about one-half of their upward movement the valve 21 will in its movements uncover the ports 20 and 24, thereby permitting the gas and air to pass from the compressing-cylinder 2^a into the power-cylinder 1^a under the compressive force exerted by the piston 10^a. Simultaneously with the attainment by the pistons 9^a and 10^a of the upward limit of their movement the valve 21 has in its movement closed the port 20 and connected 45 the port 24 with the port 25, leading to the igniter, and thereby effecting an explosion in the cylinder 1^a. As the valve 21 continues its upward movement, the ports 24 and 25 are closed, and as said valve reaches 50 the upward limit of its movement the ports 19 and 23 are opened, thereby permitting combined gas and air to flow into the cylinder 1 from the cylinder 2, into which it had been admitted by the valve 11, uncovering the 55 ports 14 and 17 during its upward movement. As the valve 21 descends, it closes the port 19 and connects the port 23 with the igniter 25, such connection of the two ports being effected when the pistons 9 and 10 have reached the 60 upward limit of their stroke.

The exhaust of the dead gases from the cyl-

inders 1 and 1^a is regulated by the valve 11, said valve in its upward movement, and near the limit thereof, connecting the port 29, leading from the cylinder 1^a, with the outlet-ports 28, and at a corresponding period on its downward movement connecting the port 26 from the cylinder 1 with the ports 28. It will be observed that the exhaust from the cylinder 1 occurs simultaneously, or approximately so, with the admission of gas and air into the compressing-cylinder 2^a, and that from the cylinder 1^a with the admission of gas and air into the cylinder 2. The exhaust-ports 26 and 29 are so located that they will 80 coact with the valve 11 in regulating the exhaust of dead gases from the cylinders 1 and 1^a.

The ports 14 and 17 and 15 and 18 should be so located with reference to each other 85 that the ports 14 and 15 will be uncovered simultaneously with or immediately after the uncovering of the ports 17 and 18, thereby avoiding any escape of gas through the air-port 16, which is constantly open. 90

We claim herein as our invention—

1. In a gas-engine, the combination of two power and compressing cylinders, a valve-chamber connected to each of said cylinders by suitable ports, and a valve located in said 95 chamber and constructed to regulate the flow of gases to and from said cylinders alternately, substantially as set forth.

2. In a gas-engine, the combination of two power and compressing cylinders, valve-chambers connected to each of said cylinders by suitable ports, and valves located in said chambers and constructed to regulate the flow of gas and air alternately to the compressing-cylinders, and thence alternately to the power-100 cylinders, substantially as set forth. 105

3. In a gas-engine, the combination of two pairs of power and compressing cylinders, a valve-chamber connected to said cylinders by suitable ports, and a valve located in said 110 chamber and constructed to co-operate alternately with each power-piston to regulate the flow of dead gases from the power-cylinders, substantially as set forth.

4. In a gas-engine, the combination of two 115 pairs of power and compressing cylinders, a valve-chamber connected to each of said cylinders and provided with an exhaust-port, and a valve located in said chamber, said valve and ports being constructed to regulate the flow 120 of gas and air to the compressing-cylinder of one pair and the exhaust of dead gas from the power-cylinder of the other pair while moving in one direction, substantially as set forth. 125

In testimony whereof we have hereunto set our hands.

ALBERT SCHMID.
J. CHARLES BECKFELD.
